UNITED STATES PATENT OFFICE.

GEORGE D. HOUSTON, OF RUSHVILLE, ILLINOIS.

CULTIVATOR.

SPECIFICATION forming part of Letters Patent No. 788,209, dated April 25, 1905.

Application filed October 6, 1904. Serial No. 227,350.

To all whom it may concern:

Be it known that I, GEORGE D. HOUSTON, a citizen of the United States, residing at Rushville, in the county of Schuyler and State of Illinois, have invented new and useful Improvements in Cultivators, of which the following is a specification.

The object of this invention is to readily convert a walking-cultivator into a riding-cultivator and provide a comfortable seat for the operator located where he can conveniently control the gangs.

A further object of the invention is to provide a wheeled carriage adapted to be attached to a walking-cultivator to convert it into a riding-cultivator and constructed to enable the riding-cultivator to make a sharp turn.

Referring to the drawings, Figure 1 is a side elevation of a riding-cultivator embodying the invention. Fig. 2 is a top plan view of the riding attachment. Fig. 3 is a sectional view on the line 3 3 of Fig. 2.

The invention consists, essentially, of a riding attachment adapted to be connected to a walking-cultivator of any desired construction, and in the drawings I have not attempted to enter into the specific details of construction of the walking-cultivator which is there shown, as it should be understood that the invention is not confined to embodiment with a cultivator of any particular type. The walking-cultivator is provided with two gangs 10, arranged side by side in the usual manner and connected to an arch 11, which carries the wheels 12 and the tongue 13. At the rear end of the tongue are hooks 14, and the gangs are provided with loops 15 to be engaged with the hooks preparatory to turning the machine around.

The riding attachment comprises a reach 16, carrying the seat 17, pivotally connected at its front end to the rear end of the tongue by a bolt 18. An arch 19, Fig. 3, is fastened by a clamp 20 to the reach 16 in the rear of the seat. Rods 21 are pivotally mounted in lugs 22 on the arch 19, and the lower ends of these rods are turned to form axles 23 for the carrying-wheels 24. The rods are held in proper relation to the arch by means of the collars 25 and flanges 26. The upper ends of

the rods 21 are pivotally connected by links 27 to a cross-piece 28, which is normally fastened to the reach by a bolt 29 or latch. In the drawings the cross-piece is shown behind the arch 19; but it could be located just as well in front of the arch, if desired. The gangs are provided with handles 30 and foot-rests 31, and the arch 19 has forwardly-projecting guide-bars 32, provided with foot-rests 33.

My invention is adapted to be embodied with any style of a walking-cultivator, and I therefore do not consider it necessary to enter into any further description of a walking-cultivator. The attachment can be readily connected with the walking-cultivator, and it forms a comfortable and substantial carriage for the operator and enables him to guide the gangs easily in their course by his feet or his hands. The carriage is also constructed to enable the machine to make a short turn at the end of a row, and this is accomplished by withdrawing the bolt 29 and then shifting the wheels 24 by operating the guide-bars 32. This can be very easily accomplished by the operator without moving from his seat, and the machine can be turned at a sharp angle at the end of the row, and the bolt 29 can be inserted in place after the machine is straightened out. My invention thus combines the advantages of a four-wheeled cultivator with the capacity of a two-wheeled vehicle for making a short turn, and it provides a comfortable seat for the operator and enables him to better control the gangs.

When it is desired to use the cultivator as a walking-cultivator, the reach 16 is disconnected from the tongue.

Without limiting myself to the exact construction and arrangement of parts herein shown and described, what I claim, and desire to secure by Letters Patent, is—

1. A four-wheeled riding-cultivator comprising a wheeled walking-cultivator, and a wheeled carriage comprising a reach pivotally connected to the rear end of the tongue of the cultivator, an arch rigidly fastened to the reach near its rear end, lugs on the sides of the upright members of said arch, rods pivotally mounted in said lugs and having their lower ends bent outward to form axles for the

carrying-wheels, means for turning said rods simultaneously to change the direction of movement of the wheels, guide-bars fastened to said axles and projecting forwardly in rear of the cultivator-gangs, and a seat on the reach above said guide-bars and in adjacent relation to the handles of the gangs.

2. A four-wheeled riding-cultivator comprising a wheeled walking-cultivator, and a wheeled carriage comprising a reach pivotally connected to the rear end of the tongue of the cultivator, an arch clamped to said reach near its rear end, lugs on the sides of said arch, upright rods pivotally mounted in said lugs

and having their lower ends bent outward to 15 form axles, carrying-wheels mounted on said axles, a cross-bar normally fastened to the reach, links pivotally connecting the ends of the cross-bar and the upper ends of said rods, forwardly-projecting guide-bars connected to 20 said axles, foot-rests on the ends of said guide-bars behind the cultivator-gangs, and a seat on the reach above said foot-rests.

GEORGE D. HOUSTON.
